UNITED STATES PATENT OFFICE

2,419,179

VALVE ROCKER ARM REFACING MACHINE

Theodore Swindle, Atlanta, Ga.

Application February 1, 1945, Serial No. 575,615

1 Claim. (Cl. 51—124)

1

This invention relates to a grinding machine designed for use in refacing valve rocker arms of internal combustion engines.

An important object of the invention is to provide a machine of this character wherein a rocker arm assembly may be mounted thereon, and will be supported vertically, to the end that the faces of the rocker arms contacting with the grinding wheels will be in full view of the person using the machine, to insure accuracy in the refacing operation.

Still another object of the invention is to provide a machine for refacing rocker arms which, because it is supported vertically, will reduce the space required to mount the machine on the usual work bench, over known rocker arm refacing machines of the horizontal type in common use.

A further object of the invention is to provide a rocker arm refacing machine embodying a main support and an adjustable bracket on the main support on which the rocker arms are mounted for refacing, the bracket and arms being adjustable to insure the grinding of the rocker arm faces, parallel with the rocker arm shaft, and on a true radius.

With the foregoing and other objects in view, which will appear as the description proceeds, the invention consists of certain details of construction and combinations of parts hereinafter more fully described and pointed out in the claim, it being understood that changes may be made in the construction and arrangement of parts without departing from the spirit of the invention as claimed.

Referring to the drawing:

Figure 1 is a side elevational view of a grinding machine constructed in accordance with the invention.

Figure 2 is a front elevational view of the machine.

Figure 3 is a sectional view taken on line 3—3 of Figure 1.

Referring to the drawing in detail, the device embodies a main supporting bracket 5, which is provided with openings 6 for the reception of securing bolts for securing the machine to a work bench or other suitable supporting surface.

At the lower end of the bracket is an arm 7, which extends rearwardly therefrom, the outer or free end of the arm 7 having an opening for the reception of the lower end of the vertical rod 8 that is secured within the opening of the arm by means of the nut 9 operating on the lower threaded end of the rod.

2

Extending upwardly from the upper end of the main supporting bracket 5 is an arm 10, which has its upper end curved rearwardly in direct alinement with the arm 7, where it is formed with an opening to receive the upper end of the rod 8, as clearly shown by the drawing. The upper end of the rod 8 is secured within the opening of the arm 10 by means of the nut 11.

The arm 10 is also provided with a bearing 11, in which the shaft 12 operates, the shaft 12 providing the supporting shaft for the grinding wheel 13. A pulley indicated at 14 is also mounted on the shaft 12, and accommodates a belt (not shown) which transmits movement to the shaft 12 and grinding wheel 13, from a motor or suitable source of power (not shown).

The support for the rocker arm assembly embodies the tubular member 15, which is mounted on the shaft 8 for rotary, as well as vertical, movement. At the lower end of the tubular member 15 is a collar 16 that is held in position on the rod 8 by means of the set-screw 17. Thus it will be seen that due to this construction, the tubular member may be adjusted around the rod 8, as well as longitudinally thereof, to bring the rocker arm supported thereby into proper grinding relation with respect to the grinding wheel 13.

At the ends of the tubular member 15 are inwardly extended arms 18, between which the rocker arm assembly is held. These arms 18 are formed with threaded openings for the reception of the adjusting screws 19 that are formed with tapered heads 20, which fit in the ends of the hollow rocker arm assembly shaft 21.

Lock nuts 22 are positioned on the set screws 19 and are adapted to engage the arms 18, setting up a binding action to lock the adjusting screws in their positions of adjustment.

The rocker arms in the present showing are indicated by the reference character 23, certain of the rocker arms being shown as moved to a position for refacing. The rocker arms 23 are held in spaced relation with respect to each other by means of spacing springs 24, positioned between the rocker of the assembly for exerting pressure on the rocker arms and restricting movement of the rocker arms longitudinally of the supporting shaft.

In operation, the valve rocker arm assembly is positioned between the arms 18 of the support and are secured in position by adjusting the set screw 19 in a manner as described. The rocker arm to be refaced is now moved into contact with the side face of the grinding wheel 13, and the

tubular member is now rotated on the rod 8 to the proper position. By supporting the rocker arms in this position during the refacing operation, the rocker arms will be ground parallel with the rocker arm shaft.

By adjusting the tubular member 15 vertically, the rocker arms of an assembly may be successively refaced.

What is claimed:

A machine for refacing rocker arms of an internal combustion engine, comprising a vertical bracket adapted to be secured to a support, a grinding wheel mounted on the bracket, a horizontal arm extending forwardly from the bracket, an upwardly and forwardly extended arm connected with the bracket and having an opening in its free end disposed in vertical alignment with the horizontal arm, a rod connecting the upwardly extended arm and the horizontal arm, a rocker arm assembly support comprising a tubular member mounted on the rod for rotary and vertical sliding movement, upper and lower spaced parallel arms extending inwardly from the tubular member, means for removably securing a rocker arm assembly between the arms of the 25

tubular member, whereby the rocker arms under treatment are supported in parallel relation to the side faces of the grinding wheel, and means for securing the tubular member in its positions of vertical adjustment on the rod.
